UNITED STATES PATENT OFFICE.

ANDREW J. McDADE, OF BROOKLYN, NEW YORK.

CALENDAR.

1,389,676.

Specification of Letters Patent. Patented Sept. 6, 1921.

Application filed July 13, 1920. Serial No. 395,923.

To all whom it may concern:

Be it known that I, ANDREW J. McDADE, a citizen of the United States, and a resident of the city of New York, borough of Brooklyn, in the county of Kings and State of New York, have invented a new and Improved Calendar, of which the following is a description.

My invention relates to perpetual calendars of the type in which separate adjustable means are provided for displaying respectively a day of the month, the name of a week day, and the name of a month.

The general object of my invention is to provide a calendar of the indicated character improved in various particulars and notably with respect to the means for displaying the day of the month prominently.

A more specific object of the invention is to provide a construction reflecting practical considerations with respect to the assemblage of the means for displaying the name of the month and the name of the week day.

The nature of the invention, its distinctive characteristics and its advantages will clearly appear as the description proceeds.

Reference is to be had to the accompanying drawings forming a part of this specification, it being understood that the drawings are merely illustrative of one example of the invention.

Figure 1 is a front view of a calendar embodying my invention, a portion of the front being broken away;

Fig. 2 is a longitudinal vertical section on the line 2—2, Fig. 1;

Fig. 3 is a transverse section on the line 3—3, Fig. 1.

In carrying out my invention in accordance with the illustrated example, a box-like body 10 is provided usually oblong in practice and open at the front side. On the said body at the front thereof I provide a front 11 forming a closure of the box. Said front presents a comparatively large opening 12 for the display of a day of the month as well as smaller openings 13, 14 above and below the opening 12 for the display respectively of the name of a week day and the name of a month.

In order to display the days of the month in succession at the opening 12, I employ a web 15 extending transversely at the back of the front 11 and across the opening 12, said web 15 bearing the days of the month. The web 15 is adapted to be wound in either di-

rection by means of elongated drums or rollers 15 disposed lengthwise of the box 10 and suitably supported in the latter. In the illustrated example one journal 16^a of each roller 15 has a bearing in a stiffener partition 17 in the body 10 while the journal 16^b at the opposite end turns in an end stiffener 18 in said body and extends through the end of the body a distance to be grasped by the fingers for turning the roller. At the opposite end of the body 10 an end stiffener 19 may be provided.

I provide in connection with the box-like body 10 and its front 11 a unit 20 which includes a sheet lying at the back of said front and disposed on the inwardly directed edge flanges 10^a of the body 10. On the back of said unit 20 I provide a disk 21 revolvably secured at its center by any suitable means indicated at 21^a. Said disk 21 has produced thereon in annular series the names of the week days and so disposed that the turning of the disk may bring the name of a given day to the opening 22 formed in the unit 20 in register with the opening 13. A second disk 23 is revolvably mounted as at 23^a on the unit 20 at the back and overlaps the disk 21 for economizing space. Said disk 23 bears in annular series the names of the months so that the name of a given month may be presented at an opening 24 in the unit 20 in register with the opening 14.

The unit 20 constitutes at the back of the opening 12 a table 20^a serving as a backing to support the web 15 and said unit 20 has cut-outs 20^b at the sides of the table 20^a through which cut-outs the web 15 runs to and from the table 20^a. The unit 20 furthermore has cut-outs 26 at the top and sides adjacent to the disk 21 so that said disk is more readily taken hold of at the periphery by the finger of the operator for shifting the disk for the successive display of the week days. Similarly, at the bottom said unit 20 has a cut-out 27 that the adjacent edge portion of the disk 23 may be the more readily taken hold of for turning. In practice, the front 11 and the sheet of the unit 20 may be fastened to the box by any suitable means, there being indicated brads 28 extending through said front and sheet and through the flanges 10^a into the partition 17 and end stiffeners 18, 19.

With the described arrangement I am enabled in a compact structure to provide large and prominent numbers for the days of the

month and the correspondingly large openings 12 therefor. At the same time compactness and convenience of assemblage is promoted as well as the maximum facility in 5 adjusting the calendar to display the successive dates.

I would state in conclusion that while the illustrated example constitutes a practical embodiment of my invention, I do not limit 10 myself strictly to the mechanical details herein illustrated, since manifestly the same can be considerably varied without departure from the spirit of the invention as defined in the appended claims.

15 Having thus described my invention, I claim:

1. A calendar of the class described including a body having a front presenting an opening for the display of a given day 20 of the month, winding rollers mounted in said body at the sides of said opening and optionally operable from the exterior of the body, a web extending transversely of said body between said rollers and across said 25 opening adapted to be moved in either direction by the rollers, a unit on said body beneath said front and constituting at said opening a table forming a backing for said web, and adjustable means carried by said 30 unit respectively above and below said table and bearing respectively the names of the week days and the months, said front of the body presenting openings at which the name of a week day and the name of a 35 month may be displayed.

2. A calendar of the class described including a body having a front presenting an opening for the display of a given day of the month, winding rollers mounted in 40 said body at the sides of said opening and optionally operable from the exterior of the body, a web extending transversely of said body between said rollers and across said opening adapted to be moved in either direction by the rollers, a unit on said body beneath said front and constituting at said 45 opening a table forming a backing for said web, said unit presenting cut-outs at the sides of said opening through which the 50 web extends from said rollers to said table.

3. A calendar of the class described including a body having a front presenting an opening for the display of a given day of the month, winding rollers mounted in 55 said body at the sides of said opening and optionally operable from the exterior of the body, a web extending transversely of said body between said rollers and across said opening adapted to be moved in either direction by the rollers, a unit on said body beneath said front and constituting at said 60 opening a table forming a backing for said web, said unit presenting cut-outs at the sides of said opening through which the web extends from said rollers to said table; 65 together with individual adjustable means supported on said unit and bearing respectively the names of the week days and of the months, said unit and said front of the structure presenting registering openings 70 for the display of the name of a week day and the name of a month.

4. A calendar of the class described including a body having a front presenting an opening for the display of a given day 75 of the month, winding rollers mounted in said body at the sides of said opening and optionally operable from the exterior of the body, a web extending transversely of said body between said rollers and across said 80 opening adapted to be moved in either direction by the rollers, a unit on said body beneath said front and constituting at said opening a table forming a backing for said web, said unit having openings at the sides 85 of said table beneath said front of the body through which openings said web passes from and to the respective rollers, a disk revolvably mounted on said unit at the back thereof and bearing the names of the week 90 days, and a second disk revolvably mounted on said unit and bearing the names of the month, said disks being disposed the one above the first-mentioned opening and the other below the same, and said front and 95 unit presenting respectively openings for the display of the name of a week day and the name of a month.

ANDREW J. McDADE.
